SKI POSITIONING MEANS FOR AIRPLANES

Herbert G. Hager, Tacoma, Wash.

Application May 24, 1949, Serial No. 94,987

4 Claims. (Cl. 244—108)

1

My present invention relates to the general art of ski landing gear for airplanes, and more specifically to a ski positioning means for airplanes.

With the greatly increased use of airplanes in cold countries there has been an unusual development in the field of ski or ski-board landing gears for such use. The majority of these observed have been constructed at considerable expense, and are designed to take care of the larger aircrafts, and many of them provide, in addition to a ski attaching means, an additional stabilizing and shock absorbing gear. Such equipment is well placed on the larger expensive aircraft. However, the field of small planes has not been given very much study.

My invention consists essentially of a unit which may be substituted for the usual wheels and brake assembly on a light airplane, and provides two parallel bars which are encircled by a plurality of strands of shock cord, one of which members is fixed with the airplane, and the other fixed to the ski mount and held in position normally by the shock cords which encircle the two members. This provides a resilient means for keeping the ski in a normal flying position, and yet allows the ski a limited degree of movement during landing or take-offs or if taxiing is done over rough snow or ice.

The principal object of my present invention, therefore, is to provide a light, simple and economical ski landing gear which may be substituted for the usual wheels on light airplanes.

A further object of my invention is to provide means that will insure that the landing ski will normally be held in its true flying position so that a minimum of air resistance will be encountered, and this without the use of additional struts or cables extending from the ski attachment to the airplane body or wings.

A further object of my invention is to provide a ski positioning means which, while presenting the ski normal to the axis of the plane in landing, will permit the ski to follow the ground contour as when an airplane lands at a considerable angle descent, or when rough snow or snow drifts and the like are encountered.

A further object of my present invention is to make use of the economical and durable shock cord in a unique arrangement to provide a yieldable positioning means for skis.

Further objects, advantages and capabilities will be apparent from the description and disclosure in the drawings, or may be comprehended or are inherent in the device.

In the drawings:

2

Figure 1 is a perspective view showing the essential elements of my invention as detached from an airplane and mounted upon a ski, parts of which are broken away;

5 Figure 2 is a vertical sectional view taken along the plane of line 2—2 of Figure 1;

Figure 3 is a vertical sectional view taken along the line of 3—3 of Figure 2, and

10 Figure 4 is a reduced scale view, similar in part to Figure 3 but showing the ski mount displaced from the airplane mount.

15 Referring more particularly to the disclosure in the drawings, the numeral 6 designates the supporting axle of my device; this may be formed to slide over the usual airplane axle employing wheels, and the same is fixed against rotation by means which must conform to the design of the plane with which my device is to be used. In many cases the perforated pad 8 can be fixedly secured to the airplane landing gear support means. Fixedly secured to axle 6 is the vertically disposed shock pillar 10. This may be secured in any manner so as to be fixed with respect to the airplane. I have illustrated a flange 12, which 20 is fixedly secured to axle tube 6, and to which pillar 10 is secured as by bolting thereto. In certain cases rotation of my device is prevented by having bolts 14 lock pillar 10 to the brake housing or back plate.

25 Positioned on shaft 6 and capable of limited rotation thereon, is the ski axle member 16. This may be provided with any suitable retaining means as the washer 18 and a split pin 20. Downwardly extending from axle 16, at divergent angles, are a plurality of supporting tubes as 22, 23 and the like, which, in turn, are fixedly secured as by welding thereto, to bearing plates, as 25 and 26. These plates in turn are fixedly secured to the landing skis 28. For additional reinforcement, the skis may have an added member 30 so as to further distribute the weight of the plane to the ski. Fixedly secured to the tubular axle 16, as by welding thereto, is the movable or ski pillar 33. This pillar, in order to gain additional stiffness for the assembly, is further secured as by welding to two of the downward extending legs, as is illustrated at 35.

30 Pillars 10 and 33 have an upper assembly that is very similar in that a central web is provided, 35 which is preferably reinforced by beaded edges, as 37 and 38. Each of the members is further provided with a bottom flange, as 40 and 42, and similarly with an upper flange, as 44 and 45. These flange members form the bearing for, and 40 the retaining means for, a plurality of resilient

shock cord bands 47. These bands encircle both of the pillars and tend, at all times, to keep them in a parallel arrangement, yet, by virtue of the resiliency of the shock cords when undue strain is placed upon the skis, a displacement of the two pillars can occur as is illustrated in Figure 4, for instance.

Now, it is well known that in landing on rough snow or ice most unusual stresses may be set up that would tend to far over-extend the shock cords 47, and to prevent this occurring I have provided the limit slots 50 and 52 in pillar 10, and in the mating pillar 33 I provide bolt holes in which I position shock or shear bolts 54 and 55. Attention is directed particularly to Figures 3 and 4. In Figure 4 it will be noted that bolt 55 has come to the end of slot 52, and therefore limits any further movement unless the force should be so great as to shear this bolt. When that occurs, the load is then transferred to bolt 54 which, owing to the fact that its slot 53 is longer and is closer to the center of revolution, can allow a continued movement of the pillars against the shock cords until the limit of slot 50 is reached. If the landing force is very severe, this bolt itself might be sheared and then reliance would have to be placed upon the shock cords and the resiliency of the skis themselves. It has been found in trial, however, that this step-by-step overload feature adds a great deal to the safety of light airplanes on skis.

It is believed that it will be clearly apparent from the above description and the disclosure in the drawings that the invention comprehends a novel construction of a ski positioning means for airplanes.

Having thus disclosed the invention, I claim:

1. A ski positioning means for light airplanes, comprising: a tubular axle adapted to be secured, fixedly, to an airplane landing gear; a vertically disposed shock pillar fixedly secured to said axle; a ski axle, co-axially disposed with and revolvably supported by said tubular axle; means for securing said ski axle fixedly to a landing ski; a ski pillar fixedly secured to said ski axle and disposed for rotation adjacent and parallel to said shock pillar; a plurality of shock cord bands disposed to encircle the upper ends of said shock pillar and said ski pillar; means for positioning and retaining said bands on each of said pillars; a plurality of arcuate slots in one of said pillars concentric with the center of rotation of said ski pillar; and shear bolts secured to the other pillar and disposed for movement in said arcuate slots.

2. A ski positioning means for light airplanes, comprising: a tubular axle adapted to be se-

cured, fixedly, to an airplane landing gear; a vertically disposed shock pillar fixedly secured to said axle; a ski axle, co-axially disposed with and revolvably supported by, said tubular axle; means for securing said ski axle fixedly to a landing ski; a ski pillar fixedly secured to said ski axle and disposed for rotation adjacent and parallel to said shock pillar; a plurality of shock cord bands disposed to encircle the upper ends of said shock pillar and said ski pillar; means for positioning and retaining said bands on each of said pillars; a plurality of arcuate slots in one of said pillars concentric with the center of rotation of said ski pillar; shear bolts secured to the other pillar and disposed for movement in said arcuate slots, and said slots having different lengths to provide a step-by-step overload shear bolt stop.

3. A ski positioning means for light airplanes, comprising: a tubular axle adapted to be secured, fixedly, to an airplane landing gear; a vertically disposed shock pillar fixedly secured to said axle; a ski axle, co-axially disposed with and revolvably supported by, said tubular axle; means for securing said ski axle fixedly to a landing ski; a ski pillar fixedly secured to said ski axle and disposed for rotation adjacent and parallel to said shock pillar; a plurality of shock cord bands disposed to encircle the upper ends of said shock pillar and said ski pillar; means for positioning and retaining said bands on each of said pillars; a plurality of arcuate slots in one of said pillars concentric with the center of rotation of said ski pillar; shear bolts secured to the other pillar and disposed for movement in said arcuate slots, and said slots being disposed at different distances from the ski axle to provide a step-by-step overload shear bolt stop.

4. A ski positioning means for light airplanes, comprising: a tubular axle adapted to be secured, fixedly, to an airplane landing gear; a vertically disposed shock pillar fixedly secured to said axle; a ski axle, co-axially disposed with and revolvably supported by said tubular axle; means for securing said ski axle fixedly to a landing ski; a ski pillar fixedly secured to said ski axle and disposed for rotation adjacent and parallel to said shock pillar; a plurality of shock cord bands disposed to encircle the upper ends of said shock pillar and said ski pillar; means for positioning and retaining said bands on each of said pillars, and additional means for connecting the shock pillar and the ski pillar to limit the amount of their relative rotation.

HERBERT G. HAGER.
